UNITED STATES PATENT OFFICE.

JOSEPH M. WEST, OF ROCKPORT, MISSOURI.

AMUSEMENT DEVICE.

1,160,802.

Specification of Letters Patent.

Patented Nov. 16, 1915.

Application filed March 12, 1915. Serial No. 14,001.

To all whom it may concern:

Be it known that I, JOSEPH M. WEST, a citizen of the United States, residing at Rockport, in the county of Atchison and 5 State of Missouri, have invented a new and useful Amusement Device, of which the following is a specification.

This invention relates to amusement devices and is more especially an improvement upon the structure disclosed in Patent 10 No. 1,079,678, issued to me on November 25, 1913.

One of the objects of the invention is to provide a broad alley for the return of balls 15 to the user after they have been thrown at a target, the said alley being provided with a plurality of outlet openings any one of which is adapted to receive the balls, whereby the score can be varied according to the 20 direction of movement taken by the ball during its return.

A further object is to provide a target made up of radially disposed paddles or 25 fingers of novel construction so mounted as to be held yieldingly in either active or inactive position.

A further object is to provide paddles or 30 fingers so shaped as to cause the ball or other thrown object to rebound in any one of a number of directions so that it thus becomes a difficult matter to so throw the ball as to cause it to return by way of a selected opening in the alley.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, can be made within the scope of what is claimed, without departing from the spirit of the invention.

45 In the accompanying drawings the preferred form of the invention has been shown.

In said drawings:—Figure 1 is a plan view of the amusement device, parts being broken away. Fig. 2 is an enlarged vertical 50 longitudinal section through the rear or target end of the device. Fig. 3 is a front elevation of the target. Fig. 4 is an enlarged section through the outer end portion of one of the fingers or paddles of the target and 55 the adjacent parts, one of the positions of said finger or paddle being indicated by

dotted lines. Fig. 5 is a perspective view of the outer end portion of one of the paddles.

Referring to the figures by characters of reference 1 designates a broad alley having a smooth top surface and formed in this alley at any desired distance from the front end thereof, is a series of openings 2 extending entirely across the alley, said series 60 being preferably substantially V-shaped. Each opening is in communication with one end of a tube 3, the several tubes employed being extended toward the front end of the 65 alley, so that should a ball pass off of the 70 alley into any one of the openings 2 it will travel along the tube in communication with said opening and be delivered to the user standing at the front end of the alley. Each 75 of these openings can be designated by a numeral, these numerals indicating different values which can be added to or subtracted from the score, according to the way in which the game is to be played.

Supported above the back end of the alley 80 is a hood or cage 4 in the front end of which is arranged a ring 5. A guard or shield 6 preferably formed of a metal fabric is erected above the alley and in front of the ring 5, the walls of this guard or shield 85 preferably converging rearwardly as shown. Hingedly mounted within the ring 5 are paddles 7 converging toward the center of the ring. Each of these paddles is preferably formed of sheet metal and is in the 90 form of a hollow cone. Each of these cones is provided with a slot 8 extending into the outer end portion thereof at the back and hinge members 9 are arranged at the sides of each slot and are connected to the ring 5. 95

The paddles 7 are normally positioned as shown in Figs. 2 and 3 and the large ends of the paddles when in these positions extend over openings 10 formed in the ring 5. Through each of these openings extends a 100 coiled spring 11, one end of which is attached to a bracket 12 secured to the outer side of the ring while the other end of the spring is secured to the adjacent paddle 7 close to the inner end wall of the slot 8 105 within said paddle. As shown particularly in Fig. 4, when the paddle 7 is in its normal or active position, the spring 11 pulls thereon along a line extending in front of the hinge 9 so that the paddle is thus held in 110 active position. When, however, the paddle is moved backwardly a short distance suffi-

cient to cause the spring to pass the hinge 9, the said spring will swing the paddle quickly to its rearward or inactive position as indicated by dotted lines in Fig. 4.

5 A guide rail 13 is arranged within the cage 4 and extends rearwardly from the ring 5 and on this rail is a slide 14 having a standard 15 connected by diverging arms 16 to a setting ring 17 normally back of and 10 concentric with the ring 5. Standard 15 is connected by a link 18 to one end of a lever 19 fulcrumed below the cage 4 and a spring 20 connected to this lever 19 serves to hold the setting ring 17 normally in position to 15 be contacted by the small end portions of the paddles 7 when said paddles are shifted backwardly out of their active positions. An actuating rod 21 extends forwardly from lever 19 and is connected to a setting lever 22 which is within convenient reach of the 20 player.

Each of the paddles 7 can be given a predetermined value. In playing the game, a ball is thrown in an attempt to strike one of 25 the paddles 7 and thus cause it to swing rearwardly against the setting ring 17. After the ball has been thrown it will pass through the ring 5 and into the cage 4 and then drop onto the rear portion of the alley 30 1. As this alley is inclined downwardly toward its front end, the ball will return along the alley and possibly enter one of the openings 2. Should it enter one of these openings, the amount represented by the opening 35 can either be added to or subtracted from the score, according to the way in which the game is being played. When it is desired to reset the paddles 7, it is merely necessary to pull forwardly on lever 22 whereupon 40 lever 19 will thrust the slide 14 forwardly and cause ring 17 to push against the paddles 7 and restore them to their normal or active positions.

What is claimed is:—

45 1. An amusement device including a ring-like member, a plurality of targets hingedly mounted therein and adapted, when in active position, to converge toward the center of the said member, a cage for receiving 50 missiles directed at the target, a broad returning alley for receiving the missiles from the cage, there being openings within the

alley for receiving the missiles while returning along the alley and returning means in communication with the openings. 55

2. An amusement device including a ring-like member, a plurality of targets hingedly mounted therein and adapted, when in active position, to converge toward the center of the said member, a cage for receiving missiles directed at the target, a broad returning alley for receiving the missiles from the cage, said alley having a plurality of openings for the reception of the missiles during their return along the alley, there being 60 spaces between the openings for the passage of the missiles, and a tubular member under the alley and extending from each of the openings. 65

3. An amusement device including a cage, 70 a plurality of radially disposed targets supported adjacent the front end of the cage, an alley inclined downwardly and forwardly from the bottom portion of the cage, there being a series of openings within the alley 75 and extending transversely thereof, said openings being spaced apart to permit the passage of missiles therebetween, and means communicating with each of the openings and extending under the alley for returning 80 to the player any missile entering the openings. 85

4. An amusement device including a cage, a target mounted in front of the cage and including inwardly converging hinged members, said cage being adapted to receive missiles directed at the target, an alley inclined downwardly and forwardly from the lower portion of the cage, there being a series of openings within the alley and extending 90 transversely thereof for the reception of missiles returning to the player, there being spaces between the openings to permit the passage of the missiles, and means under the 95 alley for delivering to the player any missiles entering any of the openings.

In testimony that I claim the foregoing as my own, I have hereto affixed my signature in the presence of two witnesses.

JOSEPH M. WEST.
